United States Patent Office

Des. 233,455
Patented Oct. 29, 1974

233,455

TOY MICROSCOPE

Mario de Matteo, Lanciano, Italy
(Via Manzoni 31, Milan, Italy)

Filed Jan. 11, 1972, Ser. No. 217,080

Term of patent 14 years

Int. Cl. D21—01

U.S. Cl. D34—15 A

Fig. 2

Fig. 3

FIG. 1 is a front perspective view of a toy microscope showing my new design;

FIG. 2 is a rear perspective view, and

FIG. 3 is a bottom plan view.

The right hand side is a mirror image of the left side except for the omission of the control switch.

I claim:

The ornamental design for a toy microscope, as shown and described.
